SIGNAL LIGHT SIGN PANEL William L. Bruner, London, Ky., assignor to
F. B. Electronics

Filed July 9, 1974, Ser. No. 487,206

Term of patent 14 years

Int. Cl. D10—06

U.S. Cl. D10—114

FIG. 1 is a front elevational view of a signal light sign panel showing my new design;

FIG. 2 is a top plan view thereof; and

FIG. 3 is a side elevational view thereof.

The rear of the panel is flat and unornamented.

I claim:

The ornamental design for a signal light sign panel, as shown and described.
